Patented Dec. 20, 1921.

UNITED STATES PATENT OFFICE.

OTTO H. JOBSKI, OF CLEVELAND, OHIO, ASSIGNOR TO THE STANDARD PARTS COMPANY, OF CLEVELAND, OHIO, A CORPORATION OF OHIO.

RIM.

1,400,956.

Specification of Letters Patent. Patented Dec. 20, 1921.

Application filed July 14, 1919. Serial No. 310,793.

To all whom it may concern:

Be it known that I, Otto H. Jobski, a citizen of the United States, and a resident of Cleveland, county of Cuyahoga, State 5 of Ohio, have invented certain new and useful Improvements in Rims, of which the following is a specification.

This invention relates to rims for vehicle wheels and more particularly to rims 10 of the so-called "quick detachable" in which a side ring is detachably seated at one edge thereof to facilitate the removal and replacing of a tire on the rim, and has for one of its objects the provision of simple and effective means for holding the side ring in seated position upon the rim.

Other objects of the invention and the features of novelty will be apparent from the following description, taken in connection with the accompanying drawings, in which:—

Figure 1 is a fragmentary side elevation of a rim embodying my invention, the rim being broken away at one point to more 25 clearly show the locking means;

Fig. 2 is a fragmentary bottom plan view of the structure shown in Fig. 1;

Fig. 3 is a fragmentary side elevation similar to Fig. 1 but showing a modified 30 structure embodying my invention;

Fig. 4 is a fragmentary bottom plan view of the structure shown in Fig. 3; and

Fig. 5 is a transverse section on the line 5—5 of Fig. 3.

In the modification illustrated in Figs. 1 and 2, 11 indicates a vehicle wheel rim having a tire-retaining flange 12 integral therewith at one edge thereof and provided, adjacent its other edge, with a circumferential 35 groove or channel 13, in which a detachable side ring 14 is adapted to be seated. The side ring 14 is transversely split, as indicated at 15, so that its ends can be sprung apart and the ring expanded sufficiently 40 to permit it to pass over the side wall of the channel 13, the ring being of such size that the ends thereof will abut when the ring is seated within the channel 13. Radially inwardly extending lugs 16 and 17 are 45 formed on the ring 14 adjacent its ends and are adapted to extend through radial openings 18 and 19 which are formed in the bottom wall of the channel 13 and are circumferentially spaced so as to leave a web 50 portion 20 of the rim between them. The

adjacent faces of the lugs 16 and 17 are inclined inwardly and toward each other, as indicated in Fig. 1, and a latch member 21 is pivotally mounted on the rim, as indicated at 22, and has a head portion 23 thereon which is adapted to engage the web portion 20 and the adjacent inclined faces of the lugs 16 and 17, being so formed that when in engaging position, it will prevent either end of the ring from moving radially outwardly. The latch member 21 may be conveniently formed, as shown, of stock metal of uniform thickness bent to the desired form and having a projection 24 at the end thereof engaging in an opening 25 in the body of the member, thereby providing a light and rigid structure which is capable of economical manufacture. The lugs 16 and 17 are preferably formed with those faces which are remote from the split 55 15 partly beveled as indicated at 26 and 27, respectively, and partly normal with respect to the circumferential extent of the ring to form shoulders 28 and 29 which are adapted to engage with the rim to interlock 60 the ring from circumferential motion thereon. It will be understood that in assembling the ring 14 on the rim 11, one of the lugs 16 or 17 will be positioned in its opening 18 or 19 and the ring will then be 65 progressively seated around the circumference of the rim. If, for instance, the lug 16 has been placed in its opening 18 with its shoulder 26 interlocked with the rim and the ring 14 has been thus progressively 70 seated, and if the other end of the ring is not properly positioned and the lug 17 thereon does not register properly with its opening 19, by reason of the engagement 75 of the beveled surface 27 of the lug 17 with the rim at one edge of the opening 19, radially inward pressure exerted on the corresponding end of the ring will cause the ring to be further contracted until the shoulder 29 interlocks with the rim to hold 80 the ring 14 against expansion. When the ring is properly seated in the channel 13, the latch member 21 may be moved from the dotted-line position shown in Fig. 2 to the full-line position shown, to engage with 85 the lugs 16 and 17 and the web portion 20 to hold the ends of the rim in their seated position.

In the structure shown in Figs. 3, 4 and 5, a latch member 30 is illustrated, which is 90

110

adapted to carry a plunger 31 for engagement with an opening 32 formed in the web portion 20 to hold the latch member in locking position. The plunger 31 has a shoulder 33 thereon which engages the body of the member 30 to limit its motion, and a leaf spring 34 attached to the latch member 30, by a rivet 35, is provided to hold the end of the plunger 31 in interlocking engagement in the opening 32.

When the detachable side ring 14 has been placed in position upon the rim, the latch member 30 is swung about its pivot and engages with the lugs 16 and 17 to hold the ring in seated position in the same manner as does the latch member 21 in the structure shown in Figs. 1 and 2. When it is desired to remove the side ring 14, a screw driver or other instrument may be inserted between the leaf spring 34 and the body of the latch member 30 to withdraw the plunger 31 from locking engagement with the web portion 20 and the latch member 30 swung on its pivot out of engagement with the lugs 16 and 17. It will also be noted that the spring 34 is extended sufficiently beyond the head of the latch member 30 to permit it to be engaged by a finger or an operating tool, to withdraw the plunger 31 from the opening 32.

Having thus described my invention, what I claim is:

1. The combination of a tire-carrying rim having a pair of radial apertures separated by a web; a transversely split side ring detachably fitted to said rim and provided

with lugs adjacent its ends adapted to project through said apertures, and having recesses in their adjacent faces; and a latch of uniform width throughout pivoted to said rim and having a head at one end adapted to be swung between said lugs to engage said web and said lugs to lock said ring in seated position.

2. The combination of a tire-carrying rim having a pair of radial apertures separated by a web; a transversely split side ring detachably fitted to said rim and provided with lugs adjacent its ends adapted to project through said apertures and having their adjacent faces oppositely inclined; and a latch pivoted to said rim and having an outwardly flaring head thereon adapted to be swung between said lugs to engage said web and the inclined faces of said lugs to lock said ring in seated position.

3. The combination of a tire-carrying rim having a pair of radial apertures separated by a web; a transversely split side ring detachably fitted to said rim and provided with lugs adjacent its ends adapted to project through said apertures and having recesses in their adjacent faces; a latch pivoted to said rim and having a head thereon adapted to be swung between said lugs to engage said web and said lugs to lock said side ring in seated position, and a spring pressed plunger carried by said head and engaging said web to hold said latch in locking position.

In testimony whereof I affix my signature.

OTTO H. JOBSKI
